UNITED STATES PATENT OFFICE.

GEORGE H. DONALDSON, OF NEW YORK, N. Y.

FOLDING HANGER FOR GARMENTS.

SPECIFICATION forming part of Letters Patent No. 395,884, dated January 8, 1889.

Application filed August 31, 1888. Serial No. 284,246. (No model.)

To all whom it may concern:

Be it known that I, GEORGE H. DONALDSON, formerly of Westville Centre, in the county of Franklin, State of New York, at present residing in the city and county of New York and State of New York, have invented a certain new and useful Improvement in Folding Hangers for Garments, of which the following is a specification.

10 Letters Patent to me, dated June 16, 1885, No. 320,230, set forth a coat-hanger adapted to properly hold coats or analogous garments—as ladies' sacks—and to conveniently fold in a small space for transportation; which in its 15 expanded condition for use can be adjusted both in width and in slope. My present improved hanger may have the same general features and possess the same advantages, serving perfectly for garments of different 20 sizes and of different slope of the shoulders.

I have devised an improvement by which the looseness of the structure as heretofore made is avoided. The improvement also gives greater strength and durability with an 25 equal amount of material. Instead of tapping each adjusting-screw from below through the thin metal of its sliding section to press with its point against the under face of the main section, I slot the main section to a sufficient length to give the required adjustability, set a screw firmly in the sliding section 30 extending downward through the slot, and apply a nut from below with a large milled head. This gives a long bearing in the nut 35 to take hold of the screw. The large head of the nut also performs another important function.

I provide a contractile spring in the form of a simple loop of rubber or of spiral wire, which, when the device is folded, may serve 40 to hold it in the closed condition. To prepare the hanger for use, the spring is removed, the hanger unfolded, and the spring applied to stretch across and join the folding parts. 45 The nuts, with their large milled heads, serve as convenient means by which the spring-loop can be readily engaged and disengaged.

The accompanying drawings form a part 50 of this specification and represent what I consider the best means of carrying out the invention.

Figure 1 is an elevation, partly in vertical section, representing the device extended for use. Fig. 2 is a corresponding plan view from below, and Fig. 3 shows the device folded for storage or transportation.

Similar letters of reference indicate corresponding parts in all the figures where they occur.

A A are the main sections, a a the longitudinal slots therein, and a' a' the inclined faces which determine by their contact with the adjustable block f the inclination at which the sections will stand and the consequent slope of shoulders with which the garment 60 will be supported.

B B are the sliding sections of sheet metal properly cut and stamped. Each is formed with lips B', which embrace the turned-down lips A' of the corresponding main section A. 70 The yoke D, with its ring C, supports all the parts by the hinge D', and the block f may be adjusted up and down by turning it as many times as may be desired around on the screw e while the hanger is in the folded condition. 75

M are screws, each having a smoothly-rounded head on its upper end and firmly set in the sliding section B, with its body extending downward through the slot a in the corresponding main section. 80

P is a nut having a large milled head, P', applied on each screw M from below. When the sliding section B has been adjusted to the correct position on the main section A, the 85 nut P is set up tightly on the screw M and firmly holds it.

W is a spring-loop of elastic material, preferably a spiral of hard brass wire containing a cord to prevent overstretching. When the hanger is extended, this spring is engaged 90 with the nuts P and holds the sections of the hanger down, maintaining a constant pressure of the faces a' against the block f and avoiding the shackle condition which would otherwise obtain. This spring may be wound around the parts to hold the device in the closed position when out of use. 95

I claim as my invention—

1. In a folding hanger for garments having sections capable of sliding to adjust the width, the screws M, rigidly fixed to the sliding sec-

tions B, in combination with the nuts P and slotted main sections A a, arranged for joint operation, as herein specified.

2. In a folding hanger for garments, the slotted main sections A a, sliding sections B, screws M, set in the latter, and nuts P, having large heads P', in combination with each other and with the spring-loop W, all arranged to serve as herein specified.

In testimony whereof I have hereunto set my hand, at New York city, this 25th day of August, 1888, in the presence of two subscribing witnesses.

GEO. H. DONALDSON.
